FLUORESCENT LAMP HOLDER

Wade E. Barre, Jr., Warren, Pa., assignor to
Sylvania Electric Products Inc., Salem, Mass.,
a corporation of Massachusetts

Application September 27, 1951, Serial No. 248,567

2 Claims. (Cl. 339—55)

1

This invention relates to lampholders for elongated lamps such as tubular fluorescent lamps having a contact pin at each end.

Such lamps have previously been provided with holders in which an insulating member, having an opening to receive the pin, is pushed back against a metal contact cup biased by a spring, for example as shown in United States Patent 2,446,154, granted on July 27, 1948 to Roger W. Haven. The depth of the contact cup is made less than the length of the lamp contact pin so that when the insulating piece meets the lamp base, the pins will push the contact cup back from the insulating piece and against the spring. This leaves the insulating piece in a mechanically "floating" condition, not backed up by the spring.

To prevent such a condition, the present invention provides a contact piece having one portion held against the back of the insulating piece by a spring and another portion of sufficient resilience to be pushed back by the contact pin without separating the first portion from the insulating piece. The holder accordingly supports the lamp not only at the latter's contact pin, but also at the end of its base. This allows a more steady and firm seat for the lamp, and is less susceptible to vibration.

In one specific embodiment of the invention, an annular portion of the contact piece is biased by a spring against the insulating member, and resilient metal fingers extend into the open center of the annular portion to contact the lamp contact pin.

One such embodiment of the invention is described in detail in the following specification, taken in connection with the accompanying drawings, in which:

Figure 1 is a view of a lamp held in a device embodying the invention;

Figure 2 is a sectional view of the device, showing its interior construction;

Figure 3 is a back view of the device;

Figure 4 is a front view of the contact piece; and

Figure 5 is a sectional profile of the same piece.

In Figure 1, the tubular lamp 16 having a base 15 at each end, is held between a forwardly-extending cup-shaped insulating plunger 6, and a fixed holder 25, the latter being attached to an end plate 26. The plunger 6 extends out of a cylindrical member 3, fixed to an end plate 20. The end plates 20 and 26 are joined to a supporting chassis member 27 by screws 28, 29.

In Figure 2, the conically-helical spring 1 extends from the back portion 2 of the hollow

2

cylindrical member 3 to the outer annular portion 4 of contact piece 5, forcing the latter against the inside surface of the front portion 14 of the insulating plunger 6, the latter being in the form of a hollow cup slidably mounted in the hollow cylindrical member 3. The insulating plunger 6 has a narrow flange 7 on its open end, the flange 7 bearing against a stop 8 at the outer end of its travel. The stop 8 is a metal ring set in a groove around the inner circumference of cylindrical member 3 near the end thereof. The large-diameter end of the spring 1 bears against the outer annular portion of contact piece 5, and the small-diameter end fits around a small cylindrical projection 30 at the back 2 of piece 3.

The contact fingers 9, 10, extend toward the axis of the plunger 6 and backwardly from the inner face 19 of said member. They extend toward each other, but do not meet, being spaced from each other at their inner ends. The piece 5 or at least the fingers 9, 10, should be of a resilient material, for example, Phosphor bronze.

A pigtail connection 18 is attached to spring 1 by solder 33 at a point intermediate the ends thereof, and extends out of the cylindrical member 3 through the opening 36 in the projection 30. The back 2 of the cylindrical member 3, shown in Figure 3, has the threaded holes 11, 12, in the bosses 31, 32, to facilitate attachment of the lamp-holder to supports such as the end plate 20.

The insulating plunger 6 has an opening 13 in its front face 14, through which the contact pin 17 of a lamp such as 16, can be inserted. The fingers 9, 10 will bend back as the pin pushes against them until the lamp base 15 bears against the front face 14, and then as the lamp is pushed further into the holder, the whole assembly 4—9—10—6 moves back together, the annular portion 4 of the contact piece 5 being kept always against the back face of member 6 by the spring 1. The lamp base 15 is thus always seated firmly against the outer surface of the front 14 of cup 6 by the pressure of spring 1, and at the same time good resilient contact is made between the lamp pin 17 and the contact fingers 9, 10. To achieve this result, the coiled spring 1 must be "stiffer" than the spring contact fingers 9, 10; that is, the spring 1 must exert somewhat greater force against the contact piece 4 than the fingers 9, 10 of that contact piece exerted against the lamp pin 15.

The pin 15 will ordinarily have a shoulder 34 of slightly larger diameter where it is fixed to the insulating boss 15. To insure that the shoulder 34 will not prevent proper seating of the end

35 of base 15 against the piece 14, the hole through which pin 17 is inserted is made slightly larger than said pin, and is flared outwardly to a diameter slightly greater than that of shoulder 34, so that the shoulder 34 fits into the hole and allows the end 35 of base 15 to seat firmly against the outer surface of member 14.

A plan view of the contact piece 4 is shown in Figure 4, and Figure 5 shows the contact fingers 9 and 10 in their position before the pin 15 is inserted and shows the fingers in phantom as 9' and 10', in their position with the pin 17 inserted.

The lampholder described is for the so-called "high voltage" end of the lamp circuit. Any suitable lampholder 25 can be used for the "low-voltage" end of the lamp circuit, for example, the holder shown for that end of the lamp in U. S. Patent 2,446,154, issued July 27, 1948 to Roger W. Haven.

What I claim is:

1. A lampholder comprising a hollow insulating support member, a hollow plunger slidable therein and having a front face with an opening for receiving a lamp contact pin, a spring 25 biasing said support member and said plunger away from each other, a contact piece held firmly against the inner surface of the front face of said plunger by said spring and having at least

5 one spring contact finger in position to meet said lamp contact pin, the spring of said contact finger being of lesser stiffness than said first-mentioned spring in order to exert a smaller force on said lamp than that exerted against the contact piece by the first-mentioned spring.

2. A lampholder comprising a hollow insulating support member, a hollow plunger slidable therein and having a front face with an opening for receiving a lamp contact pin, a spring biasing said support member and said plunger away from each other, a contact piece held firmly 10 against the inner surface of the front face of said plunger by said spring and having two spring contact fingers in position to meet said lamp contact pin, the spring of said contact fingers being of lesser stiffness than said first-mentioned spring in order to exert a smaller force on said lamp than that exerted against the contact piece by the first-mentioned spring.
